VEHICLE SPOKE WHEEL

Frank A. De Puydt and Eugene P. Conradi, Des Moines, Iowa, assignors to Dico Company, Inc., Des Moines, Iowa

Filed Dec. 14, 1970, Ser. No. 26,480
Term of patent 14 years

Int. Cl. D12—16
U.S. Cl. D14—30

FIG. 1 is a side elevational view of a vehicle spoke wheel showing our new design;

FIG. 2 is an elevational view looking in a direction diametrically of the wheel; and

FIG. 3 is a sectional view as seen along the line 3—3 in FIG. 1.

We claim:

The ornamental design for a vehicle spoke wheel, substantially as shown.
